DESIGN FOR A PIANO CASE

Peter Van Dommelen, Holland, Mich., assignor to Gulbransen Company, Chicago, Ill., a corporation of Illinois

Application March 12, 1936, Serial No. 61,590

Term of patent 3½ years

To all whom it may concern:

Be it known that I, Peter Van Dommelen, a citizen of the United States, residing at Holland, in the county of Ottawa and State of Michigan, have invented a new, original, and ornamental Design for a Piano Case, of which the following is a specification, reference being had to the accompanying drawing, forming a part thereof.

The single figure is a perspective view of a piano case showing my new design.

I claim:

The ornamental design for a piano case, as shown.

In witness whereof, I hereunto subscribe my name this 9 day of March, 1936.

PETER VAN DOMMELEN.
